(57) **CLAIM**

The ornamental design for a combined carrying case with packaged instrument components, as shown and described.

DESCRIPTION

FIG. 1 is an oblique top perspective view of a combined carrying case with packaged instrument components constructed in accordance with the invention;

FIG. 2 is a front elevational view of the combined carrying case with packaged instrument components illustrated in FIG. 1;

FIG. 3 is a right side elevation view of the combined carrying case with packaged instrument components illustrated in FIG. 1, a left side exterior view being a minor image thereof; FIG. 4 is a top plan view of the combined carrying case with packaged instrument components illustrated in FIG. 1;

FIG. 5 is a rear elevation view of the combined carrying case with packaged instrument components illustrated in FIG. 1; FIG. 6 is a top perspective view of a combined carrying case with packaged instrument components wherein the centrally located component's cover has been removed; and,

FIG. 7 is an exploded top perspective view of a combined carrying case with packaged instrument components. The broken lines illustrate portions of the combined carrying case with packaged instrument components and form no part of the claimed design.
